(57) **CLAIM**

The ornamental design for a stylus, as shown and described.

DESCRIPTION

FIG. 1 is a front and top perspective view of a stylus, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, showing an end of the stylus in a bounced position.

The broken lines in the figures illustrate portions of the stylus that form no part of the claimed design.

1 Claim, 8 Drawing Sheets

FIG. 1

FIG. 2

FIG. 3

FIG. 4

FIG. 5

FIG. 6

FIG. 7

FIG. 8
